CUP FEED MACHINE

Hans Hacklander, Tinley Park, Ill., assignor to
Union Special Machine Company, Chicago,
Ill., a corporation of Illinois

Application June 11, 1934, Serial No. 730,135

15 Claims. (Cl. 112—16)

The invention relates to new and useful improvements in a machine for stitching fabrics of the type known as a cup feed machine.

An object of the invention is to improve the operating mechanism for the stitch forming devices so that said devices may be operated by parts which are well balanced in their rotation so as to prevent undesirable vibrations in the machine.

10 A further object of the invention is to provide a simplified operating mechanism for the stitching devices wherein there are comparatively few parts and wherein all parts are positively operated.

15 A still further object of the invention is to provide a machine of the above type wherein the needle bar and the thread carrying looper supporting bar are given their endwise movement by cranks oppositely disposed on a crank shaft so as to counter-balance the weight of the rotating parts in said shaft.

20 A still further object of the invention is to provide a machine of the above type wherein the feed cups for supporting and feeding the material are carried by depending members supported from above the feed cups, and wherein the needle guards and the stitch finger cooperating with the needle in its movements and in its stitch formation, are adjustably supported 25 from the members which support the feed cups.

25 These and other objects will in part be obvious and will in part be hereinafter more fully disclosed.

30 In the drawings which show by way of illustration one embodiment of the invention—

35 Figure 1 is a view in vertical section through the machine on a plane passing through the bushing for the needle bar, the bushing for the looper bar, and the supporting bushings for the 40 shafts carrying the feed cups.

Fig. 1a is a detail in perspective showing a portion of the main actuating shaft with the opposed cranks which operate the looper bar and the needle bar.

45 Fig. 2 is a view from the rear partly in section through the main actuating shaft, partly in section through the support for the oscillating member which moves the looper bar endwise, and partly in section through the means which oscillates the looper bar and through the feed regulating means.

50 Fig. 3 is a perspective view showing the feed cups, the manner for supporting the same in the housing, and the stitch forming devices.

55 Fig. 3a is a perspective view showing the needle,

looper and spreader and the arrangement of the threads at the time when the needle point is entering the looper thread loop.

Fig. 4 is a view partly in horizontal section and partly in plan showing the upper faces of the feed cups and the needle guides and stitch finger associated therewith and the manner of supporting the same.

Fig. 5 is a plan view of the supporting bracket for the needle guards.

Fig. 5a is an edge view of the same.

Fig. 6 is a plan view of the front needle guard detached from the machine.

Fig. 7 is a plan view of the rear needle guard detached from the machine.

Fig. 8 is a plan view of the cover plate for the needle slot.

Fig. 9 is a plan view of the needle guide and stitch finger supporting plate.

The invention has to do with a machine for stitching fabrics and the type of machine known as the cup feed machine. The machine includes a main housing having an auxiliary projecting portion from which are suspended the feed cups which support and feed the fabric as it is being 20 stitched. The housing is completely closed so that no oil can escape therefrom due to the throwing of the oil by the rotating parts. The needle bar reciprocates in a horizontal line and is movable in a bushing extending through the 25 front wall of the housing and closing said housing. The actuating shaft is located in a line which lies substantially in the same horizontal plane as the line of reciprocation of the needle bar. The needle bar is directly connected to a 30 crank in the actuating shaft by a link. Associated with the needle is a thread carrying looper which moves into and out of the needle thread 35 loop and also moves from one side of the fabric sections being stitched to a position at the other 40 side thereof. A spreader associated with the needle and looper engages the looper thread loop and spreads the same so that the needle enters said loop and thus overedge stitches are formed.

The looper is carried by a bar which has both 45 an endwise and an oscillating movement. This bar is mounted in a bushing in the front wall of the housing and this bushing completely closes the housing while permitting said bar to have its endwise and oscillating movement in the bushing. The looper bar is moved endwise by a rocking member which turns about an axis located above the axis of the main actuating shaft. Attached to and movable with this member is a depending arm, the lower end of which moves in 50 55

an arc tangential to a horizontal plane containing the axis of the needle bar and also the axis of the main actuating shaft. The main actuating shaft is provided with a crank which is set 5 at substantially 180° from the crank operating the needle bar and a link connects said crank to this depending member so that it is oscillated and thus endwise movements are imparted to the looper bar. These two cranks being opposed 10 to each other provide a balanced disposition of the material which rotates about the axis of the shaft. The looper is oscillated by an eccentric strap cooperating with an eccentric on the main actuating shaft. The feed cups, as noted above, 15 are suspended from above. They are attached to shafts which rotate the same, and these shafts are mounted in supporting sleeves therefor. Attached to the supporting sleeve for the inner feed cup is a plate which extends along the 20 inner surface of the peripheral flange of the feed cup and slightly above the same. This plate is provided with a slot through which the needle passes and this slot serves as a needle guide. The plate is adjustably attached to this sleeve 25 supporting the feed cup so that it may be shifted toward and from the peripheral edge of the feed cup and the bracket carried by the sleeve on which said plate is mounted for adjustment is also mounted for vertical adjustment. The 30 stitch finger is carried by this plate and overlies the peripheral edge of the feed cups in the usual manner. The sleeve supporting the outer feed cup is provided with a flange adjacent the upper face of the feed cup and on this flange is adjustably mounted a bracket which may be shifted 35 toward and from the peripheral edge of the outer feed cup. Attached to the bracket is a front needle guard and also a rear needle guard between which the needle moves. The rear needle 40 guard overlies the peripheral edge of the feed cup and aids in stripping of the fabric therefrom after it is stitched. This bracket is also provided with a V-shaped groove which serves as a needle guide and overlying the outer end of the 45 groove is a cover plate which covers the point of the needle and aids in the supporting of the needle against any lateral strain while the looper is entering the needle thread loop.

It is thought that the invention will be better 50 understood by a detailed description of the present illustrated embodiment thereof.

The machine includes a main housing 1 which is formed with a supporting base 2 and an overhanging upper portion 3. Depending from this 55 overhanging portion of the housing is a sleeve 4 in which is mounted a shaft and attached to this shaft is the inner feed cup 5. The outer feed cup 6 is attached to the lower end of a shaft section which is mounted for rotation in a sleeve 60 7 clamped in a bracket 8. There is an upper shaft section 9 in alignment with this lower shaft section and the two are connected by a universal joint 10. Attached to this upper shaft section 9 is a gear wheel 11 which meshes with a gear wheel 12. The gear wheel 12 is attached to the shaft carrying the feed cup 5 and thus it is that the two feed cups are rotated in the same timing. It is understood, of course, that they are 65 rotated in opposite directions and the fabric is clamped between the two feed cups and supported thereby for stitching. The shaft carrying the inner feed cup is rotated by means of a clutch drum mechanism, indicated as a whole at 13. This clutch drum mechanism is operated 70 from a link 14 pivoted to an arm 15 and the

arm 15 is pivotally supported by an arm 16 mounted in the housing so that it can be adjusted to different set positions. The arm 15 is oscillated by means of an eccentric strap 17 cooperating with an eccentric on the main actuating shaft 18. The manner of operating the feed cups and the separating of the same for inserting or removing the material forms no part of my present invention, but is shown, described and claimed in my co-pending application Serial 10 No. 736,269, filed July 20, 1934.

As shown in Figs. 1 and 3 the stitch forming mechanism includes a needle 19 carried by a needle bar 20 and this needle bar is mounted for reciprocation in a horizontal line. The needle 15 bar reciprocates in a bushing 21 carried by the front wall of the main housing 1, and closing the opening therethrough so that no oil can be thrown by the actuating parts onto the material being stitched. Cooperating with the needle 20 19 is a thread carrying looper 22. This thread carrying looper 22 is carried by a looper supporting bar 23. The looper extends through a socket formed therein, and is clamped to the looper supporting bar by means of a set screw 23 24. The looper supporting bar 23 extends through a bushing 25 located in an opening in the front wall of the housing and closing said opening. The looper bar is supported at its rear end in a bushing 25a carried by the housing. 30

Cooperating with the looper and the needle is a spreader 26. Said spreader 26 is carried by a spreader supporting bar 27 which extends through a bushing 28 located in an opening in the front wall of the housing and closing said opening. 35 It will be noted that the needle bar, the spreader supporting bar and the looper supporting bar all operate in bushings which close the openings formed in the front wall so that the front wall is closed and no lubricating oil thrown by the 40 moving parts can be caused to contact with the material being stitched. It is also noted that the clutch operating drum 13 and the gear wheels 11 and 12 are all mounted in the extension of the housing and the shafts which carry and 45 operate the feed cups respectively extend through bushings in the lower wall of this extension which is close to the same and prevent any oil from being thrown through these openings onto the 50 fabric being stitched.

The stitch forming devices operate in the usual way. The needle reciprocates back and forth and as it throws out its loop the thread carrying looper enters said loop and will be moved laterally through the endwise movement of the 55 looper supporting bar as it moves into the loop so that said looper is positioned well above the edges of the fabric sections and on the other side thereof. The spreader then engages the looper thread loop extending from the eye of 60 the looper and the previous stitch and depresses the same so that the needle will pass into the looper thread loop. In Fig. 3a of the drawings there is shown the position of the looper and the spreader at the time when the looper thread 65 loop is held open for the needle to enter the same. It is not thought necessary to describe in further detail the stitch formation that is accomplished by the stitching devices disclosed. It may be again noted that the looper bar has 70 not only an endwise movement, but it has an oscillating movement in order to move the looper into and out of the needle thread loop and to carry it to a position where the spreader may cooperate therewith and by a movement in a 75

single plane to position the looper thread loop for the needle to enter.

The mechanisms for operating the stitch forming devices will now be described in detail. The 5 needle bar 20 reciprocates in a line lying in a horizontal plane passing substantially through the center of the main actuating shaft 18. The main actuating shaft in Fig. 1 is indicated by the broken line. As shown in Fig. 1a the main 10 actuating shaft is provided with a crank pin 29. This crank pin is connected to a member 30 which is formed as a part of the shaft and also a part of the crank and extends radially of the axis of the shaft. A link 31 is pivoted at 32 between spaced lugs carried by a head 33 which is attached to the needle bar 20. This link 15 cooperates with the crank 29. As the main actuating shaft 18 rotates the needle bar will be moved endwise reaching the outer end of its stroke as the link crosses dead center at the 20 right of the actuating shaft, as viewed in Fig. 1, and reaching the inner end of its stroke as the link crosses dead center at the inner side of the actuating shaft, as viewed in this figure. This 25 gives a direct thrust to the needle bar so that there is no lateral cramping of the same in its bearings and the effective movement of the link slows down as the direction of movement of the needle bar is reversed, thus making a very efficient and positive means consisting of few parts 30 for the reciprocation of the needle bar.

The looper bar 23 is given both an endwise movement and an oscillating movement as above noted. It is moved endwise by means of an oscillating arm 34, which oscillating arm is fixed to a sleeve 35 mounted on a bushing 36, which bushing in turn is mounted on a stationary shaft 37. The bushing and sleeve 35 are limited in their 35 endwise movement on the stationary shaft by an abutment lug 38 at one end and by a collar 39 at the other end which is fixed to the shaft 37 by means of a set screw 40. The arm 34 is connected at its upper end to a link 41. The link 41 is shaped so as to straddle the upper end of the arm and a 40 pivot pin 42 passing through the ends of the link 41 pivotally connects said link to the arm 34. The link at its other end carries a sleeve 43 which engages a pin 44 so that it is free to oscillate on the pin and also free to move endwise on the pin. 45 This pin is connected to a collar 45 which is mounted on the looper supporting bar 23 so that the looper supporting bar may be oscillated within said collar. At the end of the looper supporting bar is a collar 46 which is fixed to the bar. There 50 is also a collar 47 fixed to the looper bar and the collar 45 lies between the collars 46 and 47. Thus it is that the oscillations of the arm 34 through the link 41 will impart endwise movements to the looper supporting bar 23 and at the same time not 55 in any way interfere with the oscillating of the looper supporting bar. The collar 46 carries a projecting stud 46a provided with a ball stud and an eccentric strap 46b cooperates with the ball stud and an eccentric on the main actuating shaft 60 60 65 18. Thus it is that the looper supporting bar is oscillated.

The sleeve 35 carries a depending arm 48, at the lower end of which is mounted a ball stud 49. A link 50 cooperates with this ball stud and carries 70 a sleeve which cooperates with the crank 51 in the main actuating shaft 18. As shown in the perspective view (Fig. 1a) the main actuating shaft 18 is provided with a radially extending member 52 which is formed integral therewith and the 75 crank pin 51 is formed integral with this member

52. The two crank pins 29 and 51 are connected by the member 53 and this makes up this portion of the actuating shaft with the two cranks arranged so that they are substantially opposed one relative to the other. The sleeve 54 at the end 5 of the link 50 is a split sleeve and the parts thereof are secured together by the usual screws so that this permits the end of the link to be attached to the crank between the members 52, 53. The link 31 carries at its outer end a sleeve 55 which is a 10 split sleeve secured by screws in the usual way so that the outer end of the link can be connected to the crank 29.

It will be noted that the crank 29 has a slightly greater throw than the crank 51 for the reason 15 that the needle bar moves through a greater distance in its reciprocation than the looper supporting bar. It will also be noted that the two cranks are not directly opposed to each other although they are substantially opposed to each other. As 20 the main actuating shaft rotates these two cranks which are substantially opposed to each other and approximately of the same throw will balance each other so that the parts rotating with the shaft will turn about the axis of the shaft with 25 smoothness and with a minimum of resulting vibration. The reciprocating parts reverse their movement substantially at the same time.

The shaft 37 extends all the way through the abutment lug 38 and is held in a fixed position 30 by a clamping bolt 56 which passes through a sealing washer 57 and is threaded into the end of the shaft. There is the same construction at the other end of the shaft so that there is no chance of oil working out through the supporting means for 35 this stationary shaft.

The spreader bar 27 has no endwise movement but is oscillated in its supporting bushing. At the upper inner end of this spreader supporting bar there is a collar 58 which is fixed to the bar. 40 This collar carries a stud 59 provided with a ball with which an eccentric strap 60 engages. This eccentric strap 60 cooperates with an eccentric on the main actuating shaft and thus it is that the spreader supporting bar is oscillated. 45

There is also mounted on the main actuating shaft a disk 61 which runs in an oil bath and throws oil which adheres thereto from the peripheral edge thereof through the action of centrifugal force thereon and this causes a spray 50 of oil to pass all through the housing for the lubrication of the parts. This oil spraying disk forms no part of the present invention, but is shown, described and claimed in the application of George Sauer, Serial No. 718,855, filed April 3, 1934. 55

The main actuating shaft extends through bushings at each end thereof mounted in the main housing. One of these bushings is indicated in section at 62. The bushing is mounted in a bearing sleeve 63 which fits in an opening in a projecting boss 64 formed in the side wall of the housing. The same is true with the other side of the machine. The bearing sleeve is held in place by locking bolts, one of which is indicated at 65. Attached to the outer end of the shaft is a belt wheel 66.

There is a similar belt wheel 67 at the other end of the shaft. Any oil working out along the bushing 62 will be trapped in the recess 67 and will be directed in a channel 68 which leads back into the housing. This prevents any oil from 70 working out through the bearings for the main actuating shaft.

From the above it will be apparent that an operating mechanism for the stitch forming devices of a sewing machine of the cup feed type 75

has been provided wherein the parts are well balanced and completely housed so that there is no chance of any lubricating oil being thrown by the parts so as to drip from the housing and contact the fabric being stitched. It will be noted that the looper supporting bar inclines downwardly from its inner end toward the outer end over the feed cups and therefore when at the loop taking position it is close to the needle, while when it is moved laterally it is raised and moves up over the edges of the fabric sections. The spreader supporting bar is also inclined downwardly from its inner end to the outer end over the feed cups and therefore it oscillates in a plane which cuts the needle path at an angle and this enables the spreader to engage the looper thread loop at a point directly over the plane of the fabric sections and spread the loop to one side of the fabric sections for the needle to enter. This particular inclining of the looper supporting bar and the spreader supporting bar per se form no part of the present invention and is shown, described and claimed in the application of Charles F. Rubel and Anton Wyleta, filed July 25, 1932, Serial No. 624,548.

Cooperating with the needle and the stitch forming devices is a needle guide, also needle guards and a stitch finger. These devices are all carried by a depending portion 68 carried by the housing. The sleeve 4 supporting the inner feed cup extends through this depending portion of the housing. Said depending portion has a flat face on which a bracket 68 is mounted. The bracket is secured to the depending portion by screws 10 which pass through slots in the bracket extending in a direction so as to permit the bracket to be adjusted vertically and secured in different set positions by these clamping screws. The bracket at the lower end thereof is provided with a lateral seat 11 on which is mounted the shank 12 of a plate 13. This plate 13 extends outward and is curved at its outer face to conform to the shape of the peripheral flange or edge portion of the feed cup and extends all the way to and across the needle path as shown in Fig. 4. As shown in Figs. 4 and 9 said plate 13 has a curved face 14 which as noted above lies along the inner face of the peripheral flange of the inner feed cup. Said plate has an upstanding curved edge portion and there is a slot 15 formed therein through which the needle passes, and this slot serves as a needle guide to prevent the deflecting of the needle as the point thereof contacts with the material and passes through the same. The point of the needle passes first through this slot and then into the fabric sections. The shank 12 is slotted and a screw 16 passing through the slot secures this plate in adjusted position. This adjustment is horizontal and enables the curved face of the plate to be moved closer to or further away from the peripheral flange of the inner feed cup. Also mounted on this plate 13 is the stitch finger which is indicated at 17. Said stitch finger is secured to the plate 13 by clamping screws 18, 19. Said stitch finger is of the usual type. It overlies both feed cups at the fabric receiving side thereof and terminates in a point at the fabric discharge side so that the stitches formed therewith will slip off from the end of the stitch finger.

At the lower end of the sleeve 7 carrying the shaft which supports the outer feed cup is a flange 19. Fixed to this flange 19 is a bracket 80. The bracket is shown in plan view in Fig. 5. This bracket carries a forward needle guard and also

a rear needle guard and a cover plate which covers the needle slot in the bracket at the outer end of the needle path so as to prevent the bending of the needle as the looper enters the needle thread loop. The forward needle guard 5 is shown in detail in Fig. 8 and consists of a shank portion 81 provided with a slot 82 through which a clamping screw 83 passes. The outer face of this forward needle guard is curved as indicated at 84 so as to conform with the inner 10 surface of the peripheral flange on the outer feed cup. The shank 81 has a laterally extending portion 85, the left hand face of which as viewed in Figs. 4 and 6 is close to the needle path and serves to guard the needle and prevent lateral deflection thereof. The bracket as shown in Fig. 5a is provided with a V-shaped slot 86 and the needle reciprocates in this V-shaped slot which serves as a guide for the needle. The face of this forward needle guard is close to the V-shaped 20 channel 86. Attached to this bracket 80 is a rear needle guard which is shown in detail in Fig. 7. Said needle guard includes a shank 87 which is slotted and which is secured to the bracket 80 by means of a clamping screw which 25 permits the needle guard to be adjusted toward and from the peripheral edge of the outer feed cup. The outer face of this rear needle guard is curved as indicated by the broken line 88 so as to lie close to the inner face of the peripheral 30 flange of the outer feed cup. It has an overhanging portion terminating in the curved face 89 which extends slightly beyond the outer edge of the peripheral flange of the feed cup. The rear needle guard extends along the peripheral flange 35 to a point adjacent the V-shaped slot 86 where it terminates in the end portion 90. The needle passes along this V-shaped slot and between the end 90 of this rear needle guard and the end 85 of the forward needle guard. If the needle point 40 as it cuts through the fabric is deflected either to the right or the left it will contact with the needle guards which will hold it to its right line movement along the channel 86. Attached to the bracket 80 is a cover plate 91 which is secured 45 to said bracket by screws 92. This cover plate extends over the V-shaped guiding slot 86 for the needle and the needle point passes underneath the cover plate. The looper moves alongside of this cover plate 91 and as it enters the 50 needle thread loop and begins its initial pull thereon the cover plate prevents any lateral bending of the needle.

From the above it will be apparent that devices have been provided for guiding and for guarding 55 the needle and for holding it to its straight line path of movement, and these devices are capable of adjustment relative to the feed cups and are carried by the supporting means for the feed cups in such a way that they do not in any way 60 interfere with the free rotation of the feed cups.

It is obvious that minor changes in the details of construction and the arrangement of the parts may be made without departing from the spirit 65 of the invention as set forth in the appended claims.

Having thus fully described my invention, what I claim as new and desire to secure by Letters Patent, is:

1. A sewing machine including in combination 70 a main housing, feed cups carried thereby for supporting and feeding the fabric sections being stitched, a horizontal reciprocating needle bar, a needle carried thereby, a looper supporting bar mounted for endwise and oscillating movements 75

- about its axis, a looper carried thereby, a main actuating shaft mounted in said housing, cranks disposed substantially diametrically upon opposite sides of the axis of said shaft, means actuated by one of said cranks for reciprocating said needle bar, means actuated by the other crank for reciprocating said looper supporting bar so that said bar reaches the forward end of its stroke substantially as the needle bar reaches the forward end of its stroke, and means actuated from said shaft for oscillating said looper supporting bar.
2. A sewing machine including in combination a main housing, feed cups carried thereby for supporting and feeding the fabric sections being stitched, a horizontal reciprocating needle bar, a needle carried thereby, a looper supporting bar mounted for endwise and oscillating movements about its axis, a looper carried thereby, a main actuating shaft mounted in said housing, cranks disposed substantially diametrically upon opposite sides of the axis of said shaft, a link cooperating with one of said cranks and directly connected to the end of the needle bar for reciprocating the same, and means cooperating with the other crank and connected to the looper bar for reciprocating the same endwise so that said bar reaches the forward end of its stroke substantially as the needle bar reaches the forward end of its stroke.
3. A sewing machine including in combination a main housing, feed cups carried thereby for supporting and feeding the fabric sections being stitched, a horizontal reciprocating needle bar, a needle carried thereby, a looper supporting bar mounted for endwise and oscillating movements about its axis, a looper carried thereby, a main actuating shaft mounted in said housing, cranks disposed substantially diametrically upon opposite sides of the axis of said shaft, means operated by one of said cranks and connected directly to said needle bar for reciprocating the same, a member mounted for oscillation and connected to said looper supporting bar for reciprocating the same, and means cooperating with the other crank and connected to said member for oscillating the same, said member being pivoted intermediate its ends so that said looper bar will reach the forward end of its stroke substantially as the needle bar reaches the forward end of its stroke.
4. A sewing machine including in combination a main housing, feed cups carried thereby for supporting and feeding the fabric sections being stitched, a horizontal reciprocating needle bar, a needle carried thereby, a looper supporting bar mounted for endwise and oscillating movements about its axis, a looper carried thereby, a main actuating shaft mounted in said housing, cranks disposed substantially diametrically upon opposite sides of the axis of said shaft, a link cooperating with one of said cranks and connected to said needle bar for reciprocating the same, a member pivoted intermediate its ends and connected to said looper supporting bar for reciprocating the same, and a link cooperating with the other crank and connected to said member for oscillating said member.
5. A sewing machine including in combination a main housing, feed cups carried thereby for supporting and feeding the fabric sections being stitched, a horizontal reciprocating needle bar, a needle carried thereby, a looper supporting bar mounted for endwise and oscillating movements
- about its axis, a looper carried thereby, a main actuating shaft mounted in said housing, cranks disposed substantially diametrically upon opposite sides of the axis of said shaft, means cooperating with one of said cranks and connected to said needle bar for reciprocating the same, a fixed shaft mounted in said housing, a sleeve mounted for oscillation on said fixed shaft, an arm carried by said sleeve and connected to said looper supporting bar for reciprocating the same, a second arm carried by said sleeve, and a link cooperating with the other crank and connected to said second arm for oscillating the sleeve.
6. A sewing machine including in combination a main housing, feed cups carried thereby for supporting and feeding the fabric sections being stitched, a horizontal reciprocating needle bar, a needle carried thereby, a looper supporting bar mounted for endwise and oscillating movements about its axis, a looper carried thereby, a main actuating shaft mounted in said housing, cranks disposed substantially diametrically upon opposite sides of the axis of said shaft, means cooperating with one of said cranks and connected to said needle bar for reciprocating the same, a fixed shaft located above said main actuating shaft, a sleeve mounted for oscillation on said fixed shaft, an arm carried by said sleeve and projecting upwardly therefrom, means for connecting said arm to said looper supporting bar for reciprocating the same, an arm connected to said sleeve and depending therefrom, and a link connected to the lower end of said arm and to said other crank for oscillating the sleeve.
7. A sewing machine including in combination a main housing, feed cups carried thereby for supporting and feeding the fabric sections being stitched, a horizontal reciprocating needle bar, a needle carried thereby, a looper supporting bar mounted for endwise and oscillating movements about its axis, a looper carried thereby, a main actuating shaft mounted in said housing, cranks disposed substantially diametrically upon opposite sides of the axis of said shaft, the axis of said main actuating shaft being disposed in a horizontal plane in which said needle bar reciprocates, a link connected to one of said cranks and pivotally connected to the end of the needle bar for reciprocating the same, said link being substantially in line with the needle bar when said needle bar is at the ends of its reciprocation, means operated by the other crank and connected to said looper supporting bar for moving said looper supporting bar endwise, an eccentric on said main actuating shaft, and means actuated thereby and connected to said looper supporting bar for oscillating the same.
8. A sewing machine including in combination a main housing, feed cups carried thereby for supporting and feeding the fabric sections being stitched, a horizontal reciprocating needle bar, a needle carried thereby, a looper supporting bar mounted for endwise and oscillating movements about its axis, a looper carried thereby, a main actuating shaft mounted in said housing, cranks disposed substantially diametrically upon opposite sides of the axis of said shaft, the axis of said main shaft lying in a horizontal plane in which said needle bar reciprocates, a link connected to one of said cranks and to said needle bar for reciprocating said needle bar, a stationary shaft mounted in said housing and having its axis located above the axis of the main actuating shaft, a sleeve mounted for oscillation on said stationary

- shaft, an arm depending from said sleeve, the lower end of said arm moving in an arc substantially tangential to said horizontal plane containing the axis of the main actuating shaft, a link connected to said other crank and to the end of said arm for oscillating said sleeve, an arm extending upwardly from said sleeve, a link connected thereto, a collar mounted on said looper supporting bar to which said link is pivotally connected, said collar being free to turn on said looper supporting bar, and means for restraining endwise movement of the collar on the bar whereby the oscillations of said sleeve impart endwise movement to said looper supporting bar.
15. 9. A sewing machine including in combination a main housing, feed cups carried thereby for supporting and feeding the fabric sections being stitched, a horizontal reciprocating needle bar, a needle carried thereby, a looper supporting bar mounted for endwise and oscillating movements about its axis, a looper carried thereby, a main actuating shaft mounted in said housing, cranks disposed substantially diametrically upon opposite sides of the axis of said shaft, the axis of said main shaft lying in a horizontal plane in which said needle bar reciprocates, a link connected to one of said cranks and to said needle bar for reciprocating said needle bar, a stationary shaft mounted in said housing and having its axis 30 located above the axis of the main actuating shaft, a sleeve mounted for oscillation on said stationary shaft, an arm depending from said sleeve, the lower end of said arm moving in an arc substantially tangential to said horizontal plane containing the axis of the main actuating shaft, a link connected to said other crank and to the end of said arm for oscillating said sleeve, an arm extending upwardly from said sleeve, a link connected thereto, a collar mounted on said looper supporting bar to which said link is pivotally connected, said collar being free to turn on said looper supporting bar, means for restraining endwise movement of the collar on the bar whereby the oscillations of said sleeve impart endwise movement to said looper supporting bar, said stationary shaft being mounted in openings formed in the side walls of the housing and terminating at the outer faces of said side walls, a bolt threaded into each end of said stationary shaft, and a sealing washer between the head of the bolt and the casing for securing said shaft in a fixed position and for sealing the openings in which said shaft is mounted.
10. A sewing machine including in combination a main housing, feed cups carried thereby for supporting and feeding the fabric sections being stitched, a horizontal reciprocating needle bar, a needle carried thereby, a looper supporting bar mounted for endwise and oscillating movements about its axis, a looper carried thereby, a main actuating shaft located within said housing, sleeve bearings mounted in openings in the side walls of the housing and closing the same, bushings in said sleeve bearings through which said main actuating shaft extends, said sleeve bearings having means for trapping and returning lubricating oil to the housing, means actuated by said shaft for reciprocating said needle bar, means actuated by said shaft for moving said looper bar endwise, and means actuated by said shaft for oscillating said looper bar.
11. A sewing machine including in combination a main housing having a laterally projecting portion, sleeve members supported thereby, shafts

extending through said sleeve members, cooperating feed cups carried by the respective shafts at the lower ends thereof, a horizontal reciprocating needle, a needle bar carrying said needle, a main actuating shaft, means operated thereby for reciprocating said needle bar, a looper cooperating with said needle, a looper supporting bar mounted for oscillation and endwise movement carrying said looper, means operated from said shaft for moving said looper bar endwise, means operated from said shaft for oscillating said looper bar, a spreader cooperating with the looper and the needle, a spreader supporting bar, means actuated from said shaft for oscillating said spreader supporting bar, a bracket member attached to the sleeve supporting the inner feed cup and mounted thereon for vertical adjustment, a plate mounted on said bracket member having a curved face conforming to the curvature of the flange of the inner feed cup, and means for supporting said plate whereby it may be adjusted toward and from said flange, said plate having a slot formed therein serving as a guide for the needle.

12. A sewing machine including in combination a main housing having a laterally projecting portion, sleeve members supported thereby, shafts extending through said sleeve members, cooperating feed cups carried by the respective shafts at the lower ends thereof, a horizontal reciprocating needle, a needle bar carrying said needle, a main actuating shaft, means operated thereby for reciprocating said needle bar, a looper cooperating with said needle, a looper supporting bar mounted for oscillation and endwise movement carrying said looper, means operated from said shaft for moving said looper bar endwise, means operated from said shaft for oscillating said looper bar, a spreader cooperating with the looper and the needle, a spreader supporting bar, means actuated from said shaft for oscillating said spreader supporting bar, a bracket member attached to the sleeve supporting the inner feed cup and mounted thereon for vertical adjustment, a plate mounted on said bracket member having a curved face conforming to the curvature of the flange of the inner feed cup, means for supporting said plate whereby it may be adjusted toward and from said flange, said plate having a slot formed therein serving as a guide for the needle.

13. A sewing machine including in combination a main housing having a laterally projecting portion, sleeve members supported thereby, shafts extending through said sleeve members, cooperating feed cups carried by the respective shafts at the lower ends thereof, a horizontal reciprocating needle, a needle bar carrying said needle, a main actuating shaft, means operated thereby for reciprocating said needle bar, a looper cooperating with said needle, a looper supporting bar mounted for oscillation and endwise movement carrying said looper, means operated from said shaft for moving said looper bar endwise, means operated from said shaft for oscillating said looper bar, a spreader cooperating with the looper and the needle, a spreader supporting bar, means actuated from said shaft for oscillating said spreader supporting bar, said sleeve carrying the shaft supporting the outer feed cup having a projecting flange at its lower end, a bracket carried by said flange and having a V-shaped groove therein for guiding the needle, a forward needle guard adjustably attached to said bracket and

having a face lying alongside of the needle path, and a rear guard adjustably attached to said bracket and having a face lying along the other side of said needle bar for guarding the needle.

- 5 14. A sewing machine including in combination a main housing having a laterally projecting portion, sleeve members supported thereby, shafts extending through said sleeve members, cooperating feed cups carried by the respective
10 shafts at the lower ends thereof, a horizontal reciprocating needle, a needle bar carrying said needle, a main actuating shaft, means operated thereby for reciprocating said needle bar, a looper cooperating with said needle, a looper supporting bar mounted for oscillation and endwise movement carrying said looper, means operated from said shaft for moving said looper bar endwise, means operated from said shaft for oscillating said looper bar, a spreader cooperating with the
15 looper and the needle, a spreader supporting bar, means actuated from said shaft for oscillating said spreader supporting bar, said sleeve carrying the shaft supporting the outer feed cup having a
20 projecting flange at its lower end, a bracket carried by said flange and having a V-shaped groove therein for guiding the needle, a forward needle guard adjustably attached to said bracket and having a face lying alongside of the needle path, the
25 and a rear guard adjustably attached to said bracket and having a face lying along the other side of said needle bar for guarding the needle, said last named needle guard having a projecting portion overlying the flange on the outer
30

feed cup for stripping the fabric therefrom after it is stitched.

15. A sewing machine including in combination a main housing having a laterally projecting portion, sleeve members supported thereby, shafts extending through said sleeve members, cooperating feed cups carried by the respective shafts at the lower ends thereof, a horizontal reciprocating needle, a needle bar carrying said needle, a main actuating shaft, means operated thereby for reciprocating said needle bar, a looper 10 cooperating with said needle, a looper supporting bar mounted for oscillation and endwise movement carrying said looper, means operated from said shaft for moving said looper bar endwise, 15 means operated from said shaft for oscillating said looper bar, a spreader cooperating with the looper and the needle, a spreader supporting bar, means actuated from said shaft for oscillating said spreader supporting bar, said sleeve carrying the shaft supporting the outer feed cup having a projecting flange at its lower end, a bracket carried by said flange and having a V-shaped groove therein for guiding the needle, a forward needle guard adjustably attached to said bracket 20 and having a face lying alongside of the needle path, and a rear guard adjustably attached to said bracket and having a face lying along the other side of said needle bar for guarding the needle, and a cover plate attached to said bracket 25 and overlying the outer end of the V-shaped slot in the bracket guiding the needle and under which the end portion of the needle passes.

HANS HACKLANDER.
